CLAIM

I claim the ornamental design for a door latch with lever control, substantially as shown described.

DESCRIPTION

FIG. 1 is a perspective view of the door latch with lever control;

FIG. 2 is a front view of the FIG. 1 latch;

FIG. 3 is a right side view of the FIG. 1 latch;

FIG. 4 is a rear view of the FIG. 1 latch;

FIG. 5 is a left side view of the FIG. 1 latch;

FIG. 6 is a top view of the FIG. 1 latch; and,

FIG. 7 is a bottom view of the FIG. 1 latch.

1 Claim, 3 Drawing Sheets Fig. 1.

Fig. 2.

FIG. 3.

FIG. 4.

FIG. 5.

FIG. 6.

FIG. 7.
